UNITED STATES PATENT OFFICE.

ARMAND MEUNIER, OF ZEALANDIA, SASKATCHEWAN, CANADA.

POSTHOLE BOREER.

Application filed November 29, 1924. Serial No. 752,883.

The present invention pertains to a novel post hole borer adapted to bore holes for fence posts, telegraph poles and the like.

The principal object of the invention is 5 the provision of a device of this character in which the shaft carrying the auger is adapted to lie in a plumb line regardless of the position of the carrying vehicle. This object is accomplished by providing an overhead frame above the vehicle and supporting the shaft on the frame by means of a ball and socket connection.

The invention further includes special 15 gearing construction to prevent breaking of the gear train between the shaft and the engine due to relative shifting of the shaft and supporting parts.

Still further, the invention provides a 20 device for raising or lowering the auger shaft as the hole in the rail is drilled or as the auger is withdrawn from the holes. This device is constructed in two parts, one of which may be driven directly from the engine and the other by hand. Both these 25 parts are equipped with clutch mechanisms so that they may be disconnected at will.

The invention is fully disclosed in the 30 following description and in the accompanying drawings in which:

Figure 1 is a side elevation of the device; Figure 2 is a plan view;

Figure 3 is a rear elevation partly in section;

Figure 4 is a detail section of the support 35 for the auger shaft;

Figure 5 is a fragmentary elevation of the auger shaft;

Figure 6 is a section on the line 6—6 of Figure 1;

Figure 7 is a section on the line 7—7 of Figure 4; and,

Figure 8 is a section on the line 8—8 of Figure 6.

Reference to these views will now be 45 made by means of like characters which are employed to designate corresponding parts throughout.

The device comprises a platform 1 which 50 may be the bottom of a trailer or other suitable vehicle mounted on wheels 2. The base carries an engine generally designated by the numeral 3 and preferably disposed at considerable distance from the rear end of the platform. An overhead frame 4

having substantially the shape of an isosceles 55 triangle is supported by means of a pair of uprights 5 extending from the rear corners of the base 1 and joined to the sides 6 of the frame intermediate the ends thereof, as shown by the numeral 7. A pair of posts 8 extend from the sides of the frame 1, slightly rearwardly of the members 5 and are secured to the ends of the base 9 of the frame 4. The frame is further supported by a pair of braces 10 extending from the 65 platform 1 in such a manner as to intersect the members 8 and 5 at 11 and 12 respectively and secured to the triangular frame 4 near the vertex thereof as clearly shown in Figures 1 and 2. A pair of bars 13 are 70 provided for strengthening the supporting mechanism, these members being secured to the members 5, 8 and 10, as shown in Figure 1.

The portion of the triangular frame near 75 the vertex is formed in the nature of a table 14 having a central aperture 15 (Figure 4). Over the aperture are secured a pair of socket members 16 and 17 in which is received a ball 18. A square auger shaft 80 19 extends upwardly from the ball, being also received in the latter, and provided with a rounded portion 20 in and beneath the aperture. This portion carries a fixed collar 21 which rests upon a loose collar 22. 85 The latter is provided with a pair of ears 23 the purpose of which will presently be pointed out.

A tube 24 extends across the members 10 near the upper ends thereof and is provided 90 with a longitudinal slot 25. The ears 23 receive the fingers 26 of a fork 27, the handle of which extends into the tube 24 through the slot 25 and is provided with a ball 28 received inside the tube. In this manner 95 the loose collar 22 is supported.

An auger 29 of any suitable description may be secured to the shaft 19 by means of a coupling 30. It will be understood that the ball and socket construction 16—18 100 serves to hold the auger plumb regardless of the position of the frame 4.

Immediately above the ball and socket joint, the shaft 19 carries a bushing 31 with which is formed a double gear 32. The 105 ends of the bushing are reduced as at 33 and received in the ends of a yoke 34.

Across the posts 8 and near the lower

ends thereof is supported a drive shaft 35 carrying a pulley 36 connected to the pulley 37 of the engine 3 by means of a belt 38. This shaft carries a bevel pinion 39 meshing with a similar member 40 at substantially right angles thereto. The pinion 40 is mounted on one end of a shaft 41, the remaining end of which carries another bevel pinion 42. The shaft 41 is supported in bearings 41^a carried by arms 41^b extending from the members 5. On the top of the frame 4 is supported a countershaft 43 carrying a bevel pinion 44 meshing with the member 42. Adjacent the shaft is provided a bracket 45 through which passes a stub shaft 46 carrying a pinion 48 meshing with the member 44. In the yoke 34 is mounted a similar stub shaft 49 carrying a bevel pinion 50 meshing with the bevel gear 32. The free end of the shaft 49 has a sleeve 51 pivoted thereto, the sleeve receiving a slideable stem 53 pivoted to the free end of the stub shaft 46. The gearing thus far described enables the auger shaft to be driven from the engine regardless of the position of the frame, the hinged and sliding joints between the members 46, 53, 51 and 49 enabling the relative shifting of parts without breaking the train of gearing.

A countershaft 54 is mounted on the uprights 5 and carries a drum 55 and spur gear 56. A cable 57 is wound around the drum and passes over a pulley 58 supported near the vertex of the triangular frame 4, as shown in Figure 1. The free end of the cable is connected to the loose collar 22 through an apertured lug 22' (Figure 5). The shaft 35 carries a slideable sleeve, one end of which is in the nature of a clutch member 59, the other end 59' being engaged by a link 60. The base or platform 1 has a segmental rack 61 secured thereto and a lever 62 pivoted concentrically with the rack and adapted for engagement at various points thereof. The remaining end of the link 60 is pivoted to the lever 62 as indicated by the numeral 63 in Figure 3. The shaft 35 further carries a clutch member 59'' rotatable therewith and adapted for engagement by the member 59. A spring 64 surrounding the shaft 35 and engaging the end 59' and a disk 65 carried by the shaft, normally holds the two clutch members in engagement with one another.

The slideable sleeve carries a pinion 66 intermediate its ends, adapted to engage the gear 56. By means of this mechanism the cable is normally unwound from the drum as the auger is rotated, allowing the latter to descend into the earth. Likewise, the cable is wound upon the drum to lift the auger when the engine is reversed. When it is desired to turn the auger without permitting it to descend or ascend, the pinion 66 is merely brought out of engagement

with the gear 64 by operation of the lever 62. It will be seen that the collar 22 to which the cable is secured acts in permitting the auger shaft to ascend or descend. This collar is prevented from rotating by means of the fork 26-28, the latter being adapted to shift because of its connection with the tube 24 as described in connection with Figures 6 and 8.

The posts 8 support still another shaft 67 disposed above the shaft 35. This shaft also carries a slideable sleeve, one end 68 of which is formed as a clutch member, while the other end 68' receives one end of an arm 69, as shown in Figure 3. The shaft 80 also carries a clutch member 68'' adapted for engagement with the member 68. The sleeve carries a pinion 70 adapted also to mesh with the gear 56. From one of the members 8 extends a bracket 71 in which is journaled a worm 72 provided with a crank 73. The worm is in mesh with a worm wheel 74 carried by the shaft 67. The crank is turned when it is desired to raise or lower the auger by hand, the pinion 70 being normally in engagement with the gear 56 due to a spring 75 engaging the end 68' and a collar 76 on the shaft. When the gear 56 is driven from the shaft 35, the pinion 70 may be taken out of engagement with the gear by pulling the arm 69.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A post hole borer comprising a platform, an engine supported thereon, an overhead frame supported above the platform, an auger shaft having a ball and socket connection with said frame, means for turning said shaft from the engine, a second shaft supported above the platform, a drum and a gear carried by said second shaft, a cable wound around the drum and connected to said auger shaft, and means for driving said second shaft from the engine.

2. A post hole borer comprising a platform, an engine supported thereon, an overhead frame supported above the platform, an auger shaft having a ball and socket connection with said frame, means for turning said shaft from the engine, a second shaft supported above the platform, a drum and a gear carried by said second shaft, a collar fixed to said auger shaft, a loose collar surrounding the auger shaft and disposed beneath the fixed collar, a drum carried by said second shaft, a cable wound

around the drum and connected to the loose collar, and means for driving said second shaft from the engine.

3. A post hole borer comprising a platform, an engine supported thereon, an overhead frame supported above the platform, an auger shaft having a ball and socket connection with said frame, a slotted tube supported beneath the overhead frame, a fork having its handle passed through the slot in the tube, a collar fixed to said auger shaft, a loose collar surrounding the auger shaft and disposed beneath the fixed collar, the fingers of the fork being connected to the loose collar, a second shaft supported above the platform, a drum carried by said second shaft, a cable wound around the drum and connected to the loose collar, and operative connections between the second shaft and the engine and between the second shaft and the auger shaft.

4. A post hole borer comprising a platform, an engine supported thereon, an overhead frame supported above the platform, an auger shaft having a ball and socket connection with said frame, a drive shaft and a second shaft supported above the platform, a drum carried by the second shaft, a cable wound around the drum and connected to the auger shaft, a clutch mechanism adapted to establish engagement between the drive shaft and the second shaft, and an operative connection between the drive shaft and the engine.

5. A post hole borer comprising a platform, an engine supported thereon, an overhead frame supported above the platform, an auger shaft having a ball and socket connection with said frame, a drive shaft and a second shaft supported above the platform, a collar fixed to said auger shaft, a loose collar surrounding the auger shaft and disposed beneath the fixed collar, a drum carried by said second shaft, a cable wound around the drum and connected to the loose collar, a clutch mechanism adapted to establish engagement between the drive shaft and the second shaft, and operative connections between the drive shaft and the engine.

ative connections between the drive shaft and the engine and between the drive shaft and the auger shaft.

6. A post hole borer comprising a platform, an engine supported thereon, an overhead frame supported above the platform, an auger shaft supported by said frame, a drive shaft and a second shaft supported above the platform, a slotted tube supported beneath the overhead frame, a fork having its handle passed through the slot in the tube, a collar fixed to said auger shaft, a loose collar surrounding the auger shaft and disposed beneath the fixed collar, the fingers of the fork being connected to the loose collar, a drum carried by said second shaft, a cable wound around the drum and connected to the loose collar, a clutch mechanism adapted to establish engagement between the drive shaft and the second shaft, and operative connections between the drive shaft and the engine and between the drive shaft and the auger shaft.

7. A post hole borer comprising a platform, an engine supported thereon, an overhead frame supported above the platform, an auger shaft having a ball and socket connection with said frame, a drive shaft and a second shaft supported above the platform, a slotted tube supported beneath the overhead frame, a fork having its handle passed through the slot in the tube, a collar fixed to said auger shaft, a loose collar surrounding the auger shaft and disposed beneath the fixed collar, the fingers of the fork being connected to the loose collar, a drum carried by said second shaft, a cable wound around the drum and connected to the loose collar, a clutch mechanism adapted to establish engagement between the drive shaft and the second shaft, and operative connections between the drive shaft and the engine and between the drive shaft and the auger shaft.

In witness whereof I have hereunto set my hand.

ARMAND MEUNIER.
